UNITED STATES PATENT OFFICE.

ALBERT R. THOMPSON, OF SAN JOSE, CALIFORNIA, ASSIGNOR TO ANDERSON-BARN-GROVER MFG. CO., OF SAN JOSE, CALIFORNIA, A CORPORATION OF CALIFORNIA.

EXHAUST BOX.

Application filed August 18, 1922. Serial No. 582,623.

To all whom it may concern:

Be it known that I, ALBERT R. THOMPSON, a citizen of the United States, residing at San Jose, in the county of Santa Clara and State of California, have invented certain new and useful Improvements in Exhaust Boxes, of which the following is a specification.

My invention relates, generally, to that class of machines or apparatus in which filled cans or comestibles are subjected to a treating medium during their passage through the machine. Such apparatus under various names according to the nature of the treatment, are well known in the canning art, but for the sake of illustration, I have herein entitled my invention "Exhaust-box," as indicating a form of apparatus by which the "first cook" is applied prior to the sealing of the cans.

My invention relates particularly to that type of machines of this character in which the carrier for advancing the cans through the box is composed of a plurality of juxtaposed disks which, by their relative rotation, and the association of directional guides, move the cans successively from one disk to the next.

In this type of exhaust-box, the more pronounced ends sought are economy in floor space without sacrifice of an extensive can path; and also a smooth travel of the cans without danger from a possibly impeding surface. In some cases the disks have been arranged in a plurality of lines with the guide rails so arranged as to direct the cans from one disk to the next in the line throughout the length of said line, and to pass them from the last disk in said line to the first disk in an adjacent line and back throughout the length of said latter line, and then forward again in a third line, and so forth. This type of box while well adapted for plural lines, is poorly arranged in respect to securing a maximum path consistent with minimum floor space, since the path entering one side of the disk and leaving its opposite side necessarily occupies approximately only one half the surface area of each disk.

In other cases the disks have been arranged in a single unit composed of two inter-related lines, the disks in one line of the pair being staggered with relation to adjacent disks in the other line of the pair,

and the guide rails so disposed as to direct the cans from a disk in one line to the staggered adjacent disk in the next line, and back from this disk to the second disk in the first line, and thence to the second disk in the second line, and so on. This type of box is well adapted for the maximum extent of can path, for the reason that the cans entering each risk on one side and leaving said disk from the same side, are enabled to pass over nearly the full surface area of the disk. It is however not adapted, without important change, for installing in one machine a plurality of these unit pairs of lines, the difficulty being to provide the system with the proper elements to transfer the cans for a reverse travel in the box from the terminus of one such pair to the beginning of a second pair.

My invention contemplates the provision of an apparatus of this general nature in which the advantages of both types of disk machines are united and preserved, and their disadvantages obviated; and to this end my invention consists in the novel box which I shall now fully describe by reference to the accompanying drawings, in which—

Fig. 1 is a top plan view of my improved machine, partly broken to show the driving of the disks, the cover of the tank or box being removed.

Fig. 2 is a cross section of the machine on the line 2—2 of Fig. 1.

Fig. 3 is a side view taken on the line 3—3 of Fig. 1.

1 is a frame carrying a tank or box 2 of suitable construction and having a cover 2'.

The conveyer, within the box, comprises horizontally disposed disks. These are disposed in a plurality of parallel, unit pairs of lines, three pairs being here shown for the sake of illustration.

Describing the first pair, there is a line of disks 3, and a line of disks 3', the disks of the two lines being relatively staggered and the adjacent disks in each line being out of contact with each other. The entrance disk 3 of the first line, is peripherally geared by teeth 4 with the first disk 3' of the second line and said first disk of the second line is peripherally geared with the second disk 3 of the first line. The second disk 3 of the first line is geared with the second disk of the second line, and said last named disk is

geared with the third disk of the first line, and so on throughout the length of the two lines of the first unit pair. If then the first disk of the first line be rotated counter clockwise the first disk of the second line will rotate clockwise, the second disk of the first line counter clockwise, the second disk of the second line clockwise and so on.

5 are spaced can rails or guides, overlying 10 but independent of the disks. These guides enter the box around the axis of the entrance disk 3 of the first line and thence over the inner half of said disk and pass to and around the axis of the first disk of the second line over approximately its entire superficial area; thence to and about the axis of the second disk of the first line; thence to and about the axis of the second disk of the second line, and so on.

15 20 It will now be seen that a can placed upon the entrance disk 3 of the first line, between the guide rails 5, will be delivered to the first disk of the second line at one side, and will be carried around the axis of said disk 25 and be delivered from the disk at the same side it entered, to the second disk of the first line, and so on back and forth between the two lines of the unit pair, its path being thus of maximum length.

30 35 As my present improvement lies in adapting this arrangement of a pair of coacting or inter-related disk-lines for multiple unit pairs, whereby a large capacity exhaust box is provided and as, obviously, the first line 40 of the second pair adjacent to but rotatively independent of the second line of the first pair, must, in order to return the cans in a reverse direction through the box, have its disks, indicated by 3^a rotate clockwise, it follows that the can-path cannot pass directly from the clockwise rotating last disk 45 3' of the second line of the first pair, to the clockwise rotating first disk 3^a of the first line of the second pair, since these disks both rotating clockwise, must at their adjacent portions be rotating in opposite directions. It is, therefore, necessary to add to the second line of the first pair adjacent to and 50 geared with the last disk of said line a direction reversing transfer disk, indicated by R, which disk being thus geared, rotates counter clockwise, and is thus enabled through the extension of the can rails 5 about its axis to pass the can to the clockwise rotating first disk 3^a of the first line of the second pair, which last named disk passes it regularly to the first disk 3^b of the second line of said second pair. In this second pair of disk lines, the disks 3^a and 3^b 55 are related and geared as in the first pair, the direction of rotation being correspondingly reversed, whereby the cans are conveyed to the first end of the box, where another direction reversing transfer disk R' 60 is used to continue the can path to the third

65 pair of disk lines the direction of rotation of the disks 3^c and 3^d of which is like that of the first pair.

70 The initial entering disk 3 of the first line pair lies partly without and partly within the box or tank 2, projecting through the can inlet 31 thereof, and the terminal delivery disk 3^e of the last pair, in similar manner, projects through the exit opening 32 of the box or tank, Fig. 1.

75 Heat is supplied through perforated steam pipes entering the box at 6 and thence to a cross header 7 from which they branch at 8 on each side, and at 9 in the middle, and these extend the length of the box.

80 In disk boxes of this nature it is essential that the disks be either level, or better still that they be slightly tilted in a direction to present a step down from the delivery edge of one to the receiving edge of the other. It 85 is best, therefore, to provide means by which they may be adjusted either to a level or, if preferred, tilted in the proper direction to provide a step down, in either case avoiding a dangerous step up.

90 Means for accomplishing this adjustment are here shown. Each disk has a hub 10, as seen in Fig. 2, by which it is mounted for rotation on a fixed spindle 11. The spindle at its lower end is fixed by a set screw 12 in the upper end of a bearing 13, the foot of which is pivoted on a bolt 14 set in a frame member 15. The mounting is such that the bearing 13 and spindle 11 together with the disk they carry may be tilted, not however, in the direction of the line of passage of the can path from one disk to the other, but in the direction of the disk line, that is, parallel with the sides of the box. The effect of this in the arrangement of disks and the to 100 and fro can path here shown, may be seen if we assume that the disks 3 of the first line of the first pair be slightly tilted downward to the right. This will elevate the delivery edge of each of said disks relatively to the receiving edges of the disks of the second line of the first pair, and will depress the receiving edges of said first line disks relatively to the delivery edges of the second line disks, thus providing a slight step-down and better insuring against any tendency to a step-up.

105 In order to effect and control this tilting movement, the foot of the bearing 13 is provided with laterally extending lugs 16 (Fig. 120 3) on opposite sides. In each lug is fitted an adjusting screw 17 which bears upon the angle frame member 15. By manipulating these screws, by means of a suitable tool inserted through a hole 18 in the disks, Fig. 1, 110 the disk may be tilted and locked.

115 On the upper end of the disk spindle 11 is fixed the tubular top 19 of a bracket 20. Into the top of this bracket is set a screw cap 21 leaving an underlying space 22 for 125

spindle lubricant. These brackets 20, as shown in Fig. 1, are provided with wings 23 to which the can rails 5 are secured.

The power mechanism to revolve the disks 5 comprises a cross shaft 24, Fig. 2, with a controlling clutch lever 25. The shaft 24 has three bevel pinions 26, which mesh on appropriate sides with bevel gears 28 on vertical shafts 27. The upper ends of the shafts 27 carry pinions 29, the latter meshing each with an underlying gear 30 on such of the disks in each unit pair as may be selected to receive the power.

I claim:—

1. In an apparatus of the described character, the combination with a box, of a carrier therein comprising a plurality of parallel adjacent units, each unit consisting of two parallel coacting lines of juxtaposed, revolute, horizontal disks for supporting and advancing the cans; means for rotating the disks of one line of each unit in a direction opposite to the rotation of the disks of the other line of said unit; means for rotating the disks of adjacent units in relatively opposite directions; a revolute, horizontal can-transfer disk for conveying the cans from the end of one unit to the beginning of the adjacent unit; and means for directing the cans back and forth between the disks of the lines of each unit and to and from the transfer disks.

2. In an apparatus of the described character, the combination with a box, of a carrier therein comprising a plurality of paral-

lel adjacent units, each unit consisting of two parallel coacting lines of juxtaposed, revolute, horizontal disks for supporting and advancing the cans; means for rotating the disks of one line of each unit in a direction opposite to the rotation of the disks of the other line of said unit; means for rotating the disks of adjacent units in relatively opposite directions; a revolute, horizontal can-transfer disk adjacent and functionally related to the final delivery disk of the second line of one unit and the initial receiving disk of the first line of the adjacent unit; means for rotating said transfer disk in a direction opposite to that of the said final delivery disk and opposite to that of said initial receiving disk; and means for directing the cans back and forth between the disks of the lines of each unit and to and from the transfer disk.

3. In an apparatus of the described character, the combination with a box of a carrier therein comprising a pair of parallel lines of horizontal juxtaposed revolute disks for supporting and advancing the cans; means for rotating the disks of one of the lines in a direction opposite to that of the disks in the other lines; means for directing the cans back and forth between the disks of the two lines; and means for tilting each disk in the direction of the line in which it lies.

In testimony whereof I have signed my name to this specification.

ALBERT R. THOMPSON.
